UNITED STATES PATENT OFFICE.

BENJAMIN ROSS, OF BROOKLYN, NEW YORK.

SOLE STRUCTURE FOR BOOTS AND SHOES.

Application filed August 30, 1922. Serial No. 585,926.

To all whom it may concern:

Be it known that I, BENJAMIN ROSS, a citizen of the United States, and a resident of New York, borough of Brooklyn, in the county of Kings and State of New York, have invented certain new and useful Improvements in a Sole Structure for Boots and Shoes, of which the following is a full, clear, and exact specification.

This invention relates to footwear, and has for its object primarily to provide a form of sole for shoes, boots and the like whereby the bone-structure especially of the arch of the foot of the wearer will be yieldingly supported in a manner to prevent tendency of the arch to fall as well as serving to enable the arch to function normally when the wearer is walking. The invention also contemplates the provision as occasion requires of an elastic inlay in the heel part of the sole so that the force of impact of the heel of the wearer with hard surfaces will be relieved. The sole structure consists mainly of a flexible outer member with a foot portion, a shank portion and a heel portion, and on the upper face of the outer member may be a flexible inner member. On the shank portion of the outer member at its heel portion is held a bearing plate having side edges with notches. Disposed lengthwise of the shank portion under the inner member is a metallic spring strip with one of its end portions being secured to the outer member at its foot portion, while the other end of the strip slidably bears upon the notched part of the bearing plate for serving to support in its normal position the bone-structure of the arch of the foot of the wearer as well as allowing the arch to move naturally when the wearer is walking by the strip yielding upwardly and downwardly. The yielding strip is provided with hook-shaped members which movably engage the edges of the notches of the bearing plate to prevent lateral shifting of the strip from the plate.

A further object of the invention is to provide a simple, efficient and durable sole structure which may be made in any appropriate shape and size.

With these and other objects in view, the invention will be hereinafter more fully described with reference to the accompanying drawing forming a part of this specification in which similar characters of reference indicate corresponding parts in all the views,

and will then be pointed out in the claims at the end of the description.

In the drawing, Figure 1 is a top plan of one form of sole structure embodying my invention.

Fig. 2 is a sectional view taken on the line 2-2 of Fig. 1.

Fig. 3 is an enlarged perspective view of the elastic inlay used in the sole structure. 65

Fig. 4 is a top plan of the spring strip and bearing plate used in the structure, and

Fig. 5 is a section taken on the line 5-5 of Fig. 4.

The device or sole structure has an outer member 10 which may be of leather or other material in any appropriate size and shape having a foot portion 11, a curved shank portion 12 and a heel portion 13 for serving as the main sole member of a shoe, boot and the like. On the upper surface of the outer member may be an inner member, 14 also of leather or other flexible material of a size and shape similar to the size and shape of the outer member. 80

On the heel portion 13 of the inner member is an inlay 15 of rubber or other elastic material, and this inlay has a straight edge 16 and a curved edge, as 17, similar to the shape of a shoe heel. The underside of the inlay is flat, as at 18, and the upper face of the inlay gradually inclines upwardly, as at 19, toward the portion of the curved edge 17 which is opposite to the straight edge 16 so that the heel of the wearer will be cushioned to relieve the impact of the tread when walking. 90

The bone-structure of the arch of the foot of the wearer is prevented from tendency to accidental displacement from its normal position by providing a metal bearing plate 20 and a metal spring strip 21 on the shank portion 12 of the outer member 10 under the inner member 14. The bearing plate 20 may be substantially rectangular with a tapered extension, as 22, on one of its ends, and in opposite parts of the side edges of the plate intermediate its ends may be two notches 23 and 24 providing a rear portion, as 25, and a forward portion, as 26. This bearing plate is disposed lengthwise on the upper face of the outer member 10 so that the rear end of the portion 25 is adjacent to the heel portion 13 with the plate extending lengthwise of the shank portion toward the foot portion of the outer member 10. The rear portion 25 of the bearing plate is secured to the outer

member 10 by a bolt 27, Fig. 2, being driven through a hole 27^a in the portion 25 of the plate, and in the side edges of the forward portion 26 of the bearing plate are two elongated notches, as 28 and 29. The spring strip 21 is of a length as well as being curved so that it spans the shank portion 12 of the outer member 10 with its forward end lying upon the foot portion 11 of the outer member 10 and so that its rear end part movably bears upon the upper face of the portion 26 of the bearing plate 20. The forward end of the spring strip 21 is secured to the outer member by a bolt or screw 30 being driven through a hole 31 in the strip into the outer member, and the movable end of the strip is slidably held to the bearing plate 20 by two depending hook-shaped members or lugs, as 32 and 33, which are provided on opposite parts of the side edges of the slideable end part of the strip so that they movably overlap the opposed edges of the notches 28 and 29 of the portion 26 of the bearing plate. By properly curving the spring strip 21 the arch-bone of the foot of the wearer of the device will be supported against tendency to fall, while being allowed to move normally by the yielding functioning of the strip 21 in upward and downward directions when the wearer is walking, and on the upper face of the inner member may be a suitable sock lining, as 34, having a heel portion lapping upon the inlay 15.

In the foregoing description I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:

1. A sole structure for shoes and boots, comprising a flexible outer member with a shank portion, a foot portion and a heel portion, a metallic bearing plate having one part fastened to the outer member in proximity to the heel portion and having in opposite parts of the edges of its second part two notches, and a metallic spring strip

extending lengthwise on the shank portion 65 of the outer member, one end of the strip being rigidly held to the outer member at its foot portion and having its other end movably contacting with the bearing plate as well as having on opposite parts of its 69 side edges depending hook-shaped members slidably engaging the edges of the notches of said bearing plate.

2. A sole structure for shoes and boots, comprising a flexible outer member with a shank portion, a foot portion and a heel portion, a flexible inner member on the upper surface of the outer member, an elastic inlay on the heel portion of the inner member under the inner member, a metallic bearing plate having one part fastened to the outer member in proximity to the inlay, and having in opposite parts of the edges of its second part two notches, and a metallic spring strip 70 extending lengthwise on the shank portion of the outer member under the inner member, one end of the strip being rigidly held to the outer member at its foot portion and having its other end movably contacting with the bearing plate as well 80 as having on opposite parts of its side edges depending hook-shaped members slidably engaging the edges of the notches of said bearing plate.

3. A sole structure for shoes and boots, comprising a flexible outer member with a shank portion, a foot portion and a heel portion, a flexible inner member on the upper surface of the outer member, an elastic inlay on the heel portion of the inner member, a metallic bearing plate having one part fastened to the outer member in proximity to its heel portion, a metallic spring strip 90 extending lengthwise on the shank portion of the outer member under the inner member, one end of the strip being rigidly held to the outer member at its foot portion and having its other end movably contacting with the bearing plate, and means movably fastening the side edges of the bearing plate 95 and said strip together.

This specification signed and witnessed this 29th day of August A. D. 1922.

BENJAMIN ROSS.
